UNITED STATES PATENT OFFICE.

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY.

WELT GROOVING AND BEVELING MACHINE.

1,309,567.

Specification of Letters Patent.

Patented July 8, 1919.

Application filed August 12, 1918. Serial No. 249,386.

To all whom it may concern:

Be it known that I, ANDREW EPPLER, a citizen of the United States, residing at Lynn, in the county of Essex and State of Massachusetts, have invented certain new and useful Improvements in Welt Grooving and Beveling Machines; and I do hereby declare the following to be a full, clear, and exact description of the invention, such as will enable others skilled in the art to which it appertains to make and use the same.

The present invention relates to welt grooving and beveling machines, and more particularly to machines of this type employed in connection with the preparation of welting for use in the manufacture of Goodyear welt shoes.

Machines of this type form a groove in the flesh side of the welting strip for the reception of the inseam stitches, and it is not only of importance that the portion of the welting lying between the bottom of the groove and the grain side through which the stitches pass be maintained substantially uniform in thickness, but it is also of importance that the groove extend continuously the length of the welting strip and be of sufficient depth throughout to properly receive the stitches independently of any considerable variations in the thickness of the welting strip.

Accordingly, an object of the present invention is to produce an improved welt grooving and beveling machine whereby a continuous groove of adequate depth throughout the length of the welting strip, for the reception of the inseam stitches, can be formed in such a manner that the portion of the welting strip lying between the bottom of the groove and the grain side through which the stitches pass can be maintained at an adequately uniform thickness independently of any considerable variations in the thickness of the welting strip.

Another object of the invention is to provide improved means for actuating an edge guide for the welting strip as it passes through the machine, and by which the welting is efficiently guided without danger of buckling or otherwise cramping the welting by excessive pressure exerted on its edges.

With these and other objects in view the various features of the invention consists in certain novel features of construction,

combinations and arrangements of parts hereinafter described and claimed, the advantages of which will be obvious to those skilled in the art from the following description.

60

In the accompanying drawings illustrating the preferred form of the invention, Figure 1 is a view in front elevation of the head of a welt grooving and beveling machine embodying my invention; Figs. 2 and 65 3 are enlarged vertical and horizontal sectional views respectively taken on the lines 2-2 and 3-3 of Fig. 1; Fig. 4 is a vertical sectional view taken on the line 4-4 of Fig. 3, looking from the rear of the 70 machine; Fig. 5 is a vertical sectional view taken on the line 5-5 of Fig. 4; and Fig. 6 is a view similar to a portion of Fig. 3, but with parts shown in horizontal section.

The welt grooving and beveling machine 75 illustrated in the drawings has substantially the same general construction and mode of operation as the machine shown in the patent to Morrill, No. 1,204,897, dated November 14, 1916. The welting strip to be acted 80 upon is led from one of the holders or troughs 10, 10 over a guide roll 11, through a guide 12, and between a feed roll 14 and a co-operating work supporting roll 16. As the welting reaches the bite of the feed and 85 supporting rolls it is acted upon by a grooving knife 18 and a bevel-knife 20, and passes down through a revolving coiling tube 22 by which it is formed into a coil at the base of the machine frame. The feed roll 14 90 is mounted in fixed bearings in the machine frame and the supporting roll 16 is mounted in bearings in a carrier 24 which is slidably mounted in the machine frame. A coil spring 26 is mounted between an ad- 95 justing screw 28 in the machine frame and carrier 24 to yieldingly press the supporting roll toward the feed roll to clamp the welting between them. While the welting is being grooved and beveled it is held 100 against an inner edge guide 29 by means of an outer edge guide 30, which is slidably mounted in the carrier 24. To open up the machine to permit welting to be easily threaded therethrough, the carrier 24 may 105 be shifted by a hand lever 31 to move the supporting roll away from the feed roll and at the same time withdraw the outer edge guide from the inner edge guide. The parts above described may have the same con-

100

105

110

struction and mode of operation as the parts shown and described in the patent referred to, and reference is hereby made to said patent for a detailed description of these parts.

In the illustrated embodiment of the invention said troughs 10, 10 for the rolls of welting strips are formed in the upper portion of a holder 32, which holder is pivoted 10 at 34 to the machine frame to enable the operator to severally bring troughs 10, 10 into alinement with the guide 12 and the welting engaging portions of the feed rolls of the machine, thereby permitting the feed rolls 15 to draw a welting strip from its trough without deflecting the strip sidewise. The holder 32 is retained in the desired positions by a spring pressed detent 35 mounted therein engaging one of the sockets 36, 36 in the 20 machine frame (Figs. 1 and 2).

The welting is positioned, as it passes between the feed and supporting rolls, so that one edge projects beyond the forward ends of the rolls. This projecting edge of the 25 welting is supported on one side by a work support 38 (Figs. 1 and 3). It is of importance that the work support be maintained in a fixed position with relation to the yieldingly mounted supporting roll. Accordingly, I form the work support on a plate 30 42 secured to the front of the supporting roll carrier 24. The surface of the work support is concentric with and forms a continuation of the surface of the supporting roll 35 and extends circumferentially to the bite of the rolls or to a plane passing through the axes of both rolls.

The means for actuating the outer edge guide 30 comprises a plunger 44 (Fig. 3) 40 mounted in an aperture in the frame of the machine and pressed outwardly against the arm 46 of lever 48 by a spring 50, the tension of which spring is made adjustable by the screw 52 threaded into said aperture. The lever 48 is pivoted on a stud 54 on the supporting roll carrier, and the movement thereof by the plunger in one direction is limited by an arm thereof engaging an adjustable stop screw 56 threaded into 50 said carrier. The lever 48 is connected to an arm 58 of a lever 60 through a comparatively light spring 62 mounted on a screw 64 threaded into the arm 58 and extending loosely through an aperture in 55 an arm of the lever 48. The lever 60 is pivoted on said stud 54 above the lever 48 and the end of its arm 58 engages a recess in the end of the shank 66 of the edge guide 30. Said shank 66 extends rearwardly 60 from the edge guide 30 and is slidably mounted in the bearing 68 on the supporting roll carrier. The spring 62 which, through the arm 58 and shank 66, tends to press the edge guide 30 toward the inner edge guide 65 29, is of suitable strength to cause the welting

ing to be efficiently guided without danger of buckling or cramping the welting. When the supporting roll carrier 24 is actuated to separate the rolls 14 and 16, an arm of the lever 60 engages a stud 72 on the machine 70 frame thereby swinging said lever sufficiently to effect the desired amount of retraction of guide 30. The guide 30 is returned to its effective position by the action of the plunger spring 50. 75

The outer edge guide 30 and its operative connections may be adjusted to different width welting strips so as to permit the edge guide by the action of spring 62 to exert the desired amount of yielding pressure on the 80 different width welting strips. This adjustment is effected by means of the adjustable stop screw 56 which is adapted to be turned to vary the limit to which the outer edge guide 30 is moved by the action of the plunger spring 50. 85

It has heretofore been proposed to form a groove in a welting strip of a uniform depth throughout its length. This is objectionable, however, in case any considerable 90 variations occur in the thickness of the welting strip, on account of the resulting variations in thickness of the portion of the welting lying between the bottom of groove and the grain side through which the stitches 95 pass. It has also been proposed to form the groove of a depth varying with the variations in thickness of the welting strip, thereby leaving said portion of the welting through which the stitches pass of a uniform 100 thickness throughout, but it has been found that this effects little or no grooving of the thinner portions of welting varying considerably in thickness. To avoid these objectionable features, the mechanism for operating 105 the grooving knife of the illustrated machine is controlled by the variations in thickness of the strip of welting in such a manner that the grooving knife is caused to effect the grooving of the welting to a depth 110 varying directly with the variations in thickness of the welting but to a less degree. Both the depth of the groove and the thickness of the material at the bottom of the groove are thus varied when variations occur 115 in the thickness of the welt strip. The variations thus effected in the depth of the groove and in the thickness of the material at the bottom of the groove, however, are not sufficient to objectionally affect the welting even when the welting varies considerably in thickness. To effect the desired 120 grooving of the welting strip, the grooving knife is mounted on and about midway between the ends of a depending lever 76 pivoted on a stud 78 on the frame of the machine and having its lower end connected by a link 80 to a lug 82 formed on the plate 42 of the work supporting roll carrier 24. By this mechanism, it will be seen that the 125 130

grooving knife is moved back and forth with the work supporting roll when variations occur in the thickness of the welting strip, but such movement of the grooving knife 5 will be less in extent than the corresponding movement of the work supporting roll and its carrier, because the cutting edge of the grooving knife is at a less distance from the pivot of the depending lever 76 than the point of connection of the carrier and depending lever is from said pivot, thereby effecting the desired minute variations in the depth of the groove formed by the grooving knife relative to the variations in thickness 10 of the welting strip.

The grooving knife is mounted for lateral adjustment by being secured to a slide 86 mounted on a block 87 formed on the depending lever. The adjusting movement 20 of the slide 86 is effected by means of a screw 90 threaded into an aperture in said block and having a reduced portion of its head engaged by a yoke 92 on the slide.

In order to vary the general depth of the 25 groove, the grooving knife may be moved by the depending lever toward and from the work supporting roll by adjusting the link 80, which link is made longitudinally adjustable by means of the turnbuckle 94.

30 The movement of the grooving knife and the depth of the groove formed by the grooving knife is indicated on a dial 96 at the upper right hand corner of the front of the frame of the machine by a pointer 35 98 pivoted at 100 on the frame and having a depending arm 101 thereof operatively connected by a link 102 to the depending lever 76.

The beveling knife 20 (Figs. 1, 3, 5 and 6) 40 is adjustably mounted in the usual clamp 103 carried by a slide 104, and is arranged to act upon the welt at the bite of the rolls beneath the support 38. The slide 104 is mounted in a block 106 and is adapted to 45 be moved therein to laterally adjust the beveling knife by means of a screw 108 threaded into an aperture in said slide and having a reduced portion of its head in engagement with a yoke 110 on the block 106. The block 106 is vertically pivoted on a 50 bracket 112 projecting from the plate 42, and said block may be swung outwardly on its pivot to permit inspection of the welting at the point of operation and to 55 allow the knives to be sharpened and adjusted without dismantling the machine. The bracket 112 has the spring pressed detent 114 to engage a socket or aperture 116 in the block 106 to lock the latter in operative 60 position. The block 106 carries the inner edge guide 29.

To permit inspection of the welting during the operation of the machine and after the welting has passed the knives but before it has entered the guide 22, a finger

117 (Figs. 1 and 3) is pivoted on a stud 118 on the frame of the machine and is normally held out of engagement with the welting by a coiled spring 119. The operator may readily swing this finger to bring 70 the welting into view to inspect the work.

While the features described above are well adapted for use in the type of machine illustrated in the drawings, it is to be understood that except as defined in the claims 75 certain features of the invention are not limited to use in a machine embodying any or all of the other features.

The preferred form of the invention having been thus described, what is claimed is: 80

1. In a machine for preparing welting, the combination of means for supporting a welting strip of varying thickness, with means for forming a groove in the welting strip of a depth varying directly but to a 85 less degree with the variations in thickness of the welting strip.

2. A machine for preparing welting having, in combination, a feed roll to act on a welting strip of varying thickness mounted 90 in fixed bearings, a coöperating work supporting roll, a carrier for the work supporting roll movable toward and from the feed roll, and a grooving knife actuated through movement of the carrier as the welting strip is being fed by the rolls to effect 95 the formation of a groove in the welting strip of a depth varying directly but to a less degree with the variations in thickness of the welting strip. 100

3. A machine for preparing welting having, in combination, a feed roll to act on a welting strip mounted in fixed bearings, a coöperating work supporting roll, a carrier for the work supporting roll movable toward and from the feed roll, a lever pivoted 105 at one end on a fixed stud and connected at its other end to the carrier, and a grooving knife to act on the welting strip mounted on the lever. 110

4. A machine for preparing welting having, in combination, a feed roll to act on a welting strip mounted in fixed bearings, a coöperating work supporting roll, a carrier for the work supporting roll movable 115 toward and from the feed roll, a depending lever pivoted on a fixed stud and connected at its lower end by an adjustable link to the carrier, and a grooving knife to act on the welting strip mounted on the depending lever. 120

5. A machine for preparing welting having, in combination, a feed roll to act on a welting strip mounted in fixed bearings, a coöperating work supporting roll, a carrier 125 for the work supporting roll movable toward and from the feed roll, a grooving knife to form a groove in the welting strip connected to the carrier so as to be moved thereby, a dial, and a pointer connected to 130

the grooving knife to indicate on the dial the depth of the groove formed by the grooving knife.

6. A machine for preparing welting having, in combination, means for supporting a welting strip, an edge guide for the welting strip, a spring for moving the edge guide toward the welting strip, a stop for limiting the movement of the edge guide by the action of the spring, and a relatively light spring to sustain the edge guide in yielding engagement with the welting strip.

7. A machine for preparing welting having, in combination, means for supporting a welting strip, an edge guide for the welting strip, means for moving the edge guide toward the welting strip, a stop for limiting said movement of the edge guide toward the welting strip, a relatively light spring to sustain the edge guide in yielding engagement with the welting strip, and means for retracting the edge guide.

8. A machine for preparing welting having, in combination, means for supporting a welting strip, an edge guide for the welting strip, a spring actuated lever to move the edge guide toward the welting strip, a stop for limiting the movement of the edge guide by said lever, a spring disposed between the edge guide and said lever to sustain the edge guide in yielding engagement with the welting strip, and means including said lever for positively retracting the edge guide.

9. A machine for preparing welting having, in combination, feed rolls for feeding a welting strip, means for moving one of the rolls toward and from the other, an edge guide for the welting strip, a lever connected to the edge guide, means to actuate the lever to move the edge guide toward the welting strip, an adjustable stop for limiting the movement of the edge guide by said lever, a spring disposed between the edge guide and said lever to sustain the edge guide in yielding engagement with the welting strip, and means actuated by said means for moving one of the feed rolls to retract the edge guide.

10. A machine for preparing welting having, in combination, a feed roll, a coöperat-

ing work supporting roll, means for guiding a welt strip with one edge projecting beyond the ends of the rolls, a work support for the projecting edge of the welting having a welt supporting surface concentric with the surface of the work supporting roll, a beveling knife, a knife block for said beveling knife mounted to move relative to said support about a pivot substantially normal to a plane passing through the axes of the rolls, and means for holding said block in operative position.

11. In a machine for preparing welting, the combination with feed rolls for feeding a welting strip, and a knife to act on the welting strip, of a holder for a plurality of rolls of welting strips pivoted to permit the holder to be swung to bring the rolls of welting strips severally into a position relative to the welting engaging portions of the feed rolls whereby the strips may be successively drawn from the holder without deflecting them sidewise.

12. A machine for preparing welting having, in combination, feed rolls for feeding a welting strip between them, a knife to act on the welting strip, a guide constructed and arranged to receive the welting strip and to permit its passage therethrough, and a pivoted finger disposed between the feed rolls and the guide and adapted to be moved to deflect a portion of the welting strip outwardly.

13. A machine for preparing welting having, in combination, means for supporting a welting strip, and means for forming a groove in the welting strip while leaving the material at the bottom of the groove of a thickness varying directly with the thickness of the welting strip but to a less extent.

14. A machine for preparing welting having, in combination, means for supporting a welting strip, means for forming a groove in the welting strip, and means for varying both the depth of the groove and the thickness of the material at the bottom of the groove when the welting strip varies in thickness.

ANDREW EPPLER.
